[57] CLAIM

The ornamental design for a terminal for preventing the unauthorized use of a credit card, as shown and described.

DESCRIPTION

FIG. 1 is a perspective view of a terminal for preventing the unauthorized use of a credit card showing my new design with a credit card being shown in broken lines for illustrative purposes only and forming no part of the claimed design;

FIG. 2 is an end elevational view thereof;

FIG. 3 is an end elevational view thereof opposite that shown in FIG. 2;

FIG. 4 is a rear elevational view thereof;

FIG. 5 is a front elevational view thereof;

FIG. 6 is a top plan view thereof; and,

FIG. 7 is a bottom plan view thereof.

FIG. 1

FIG. 2

FIG. 3

FIG. 4
